[57] CLAIM

The ornamental design of a plunger tip for character printer hammer unit, as shown and described.

DESCRIPTION

FIG. 1 is a perspective view of a plunger-tip for character printer hammer unit showing our new design;

FIG. 2 is a side elevational view;

FIG. 3 is a cross-sectional view taken on line III—III of FIG. 2; and

FIG. 4 is a side elevational view on a reduced scale. The broken line showing of other portions of the hammer assembly and printer in FIG. 4 is for illustrative purposes only and forms no part of the claimed design.
